Des. 223,198
Patented Mar. 28, 1972

223,198

STACKABLE HOUSING UNIT FOR ELECTRONIC EQUIPMENT

Karl Lang, Uerikon, and Hans Steiner, Greifensee, Switzerland, assignors to Mettler Instrumente AG, Zurich, Switzerland

Filed Sept. 10, 1970, Ser. No. 24,936

Term of patent 14 years

Int. Cl. D14—02

U.S. Cl. D26—5

Fig. 1

FIG. 1 is a perspective view of the stackable housing unit with the U-shaped leg means in the extended position;

FIG. 2 is a front view of the housing with the leg means in the retracted position; and

FIGS. 3-6 are back, side, top and bottom views, respectively, of the housing.

We claim:

The ornamental design for a stackable housing unit for electronic equipment, as shown.
